US00D769876S

(12) **United States Design Patent** (10) Patent No.: **US D769,876 S**
(45) Date of Patent: **** Oct. 25, 2016**

(54) **COMPONENT FOR ELECTRONIC DEVICE**

(71) Applicant: **Apple Inc.**, Cupertino, CA (US)

(72) Inventors: **Shota Aoyagi**, San Francisco, CA (US);
Tyler B. Cater, San Jose, CA (US);
Sawyer Isaac Cohen, Sunnyvale, CA
(US); **Richard P. Howarth**, San
Francisco, CA (US)

(73) Assignee: **Apple Inc.**, Cupertino, CA (US)

(**) Term: **14 Years**

(21) Appl. No.: **29/501,050**

(22) Filed: **Aug. 29, 2014**

(51) **LOC (10) Cl. 14-02**

(52) **U.S. Cl.**

USPC **D14/432**

(57) **CLAIM**

The ornamental design for a component for electronic device, as shown and described.

DESCRIPTION

FIG. 1 is a front perspective view of a component for electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
